SEAL TAG

Hans F. Stoffel, Scarsdale, N. Y.

Application April 1, 1947, Serial No. 738,659

7 Claims. (Cl. 292—310)

1

This invention relates to seal tags and more particularly to tamper-proof seal tags or sealing devices for attachment to articles to be sealed and identified, the tags being substantially made from metal, such as aluminum or plastic, plastic composition and any other suitable material.

It is one of the objects of the invention to provide an improved and efficient seal tag which may be readily adjusted with respect to the article to which said seal tag is applied and which is self-locking. This new seal tag includes a hollow, annular rim in which tie means is accommodated and which projects beyond said rim through openings or slots thereof. The tie means includes a loop portion for encompassing an article or part thereof and has one or two loose ends or legs which may be grasped by the hand of a person for manipulating the tag and for locking the same in place.

It is another object of the invention to provide means affording the manufacture of inexpensive seal tags or devices by mass production method and the operation of such seal tags in a simple and secure manner.

A further object of the invention is to provide means facilitating the severance of tie means or a part thereof in locked position of said seal tag.

Yet, another object of the invention is to provide means conducing to a sturdy and strong seal tag or device in which any suitable tie means, such as cord, twine, wire, etc. may be employed whose loop portion may be readily regulated as to its size (extent) and form.

Other objects and advantages of the invention will become more apparent from the following detailed description when considered in connection with the accompanying drawing which is submitted for the purpose of only illustrating certain embodiments of the invention, reference being further had to the attached claims.

In the drawing, wherein similar reference characters refer to similar parts throughout the several views,

Fig. 1 is a perspective view of the cup of which the tag made in accordance with this invention is manufactured;

Fig. 2 is a front-elevational view of a seal tag as applied to an article and shown before the free ends or legs of the tie means are pulled tight;

Fig. 3 is a front-elevational view of the tag of Fig. 2 in a somewhat modified form and before it is attached to an article;

Fig. 4 is a front-elevational view of a tag in modified form but similar to that shown in Fig. 3;

2

Fig. 5 is a rear view of the tag made in accordance with this invention and as seen in Fig. 3, but shown as secured to an article;

Fig. 6 is a sectional view taken along line 6—6 of Fig. 3.

Referring now more particularly to the drawing and before explaining the present invention in greater detail, it is to be understood that the invention is not limited in its application to the 10 details of construction and arrangement of parts as illustrated since the invention is capable of other embodiments and of being practiced or carried out in various ways.

The novel seal tag is manufactured from a cup 20 of suitable material as hereinabove mentioned, which cup is shown in perspective in Fig. 1. This cup 20 has a bottom or plate surface 1, which is preferably flat and has further an upwardly extending rim 21 consisting of sections 2 and 3 20 which are formed by slots 4 and 5 cut across said rim 21, said slots normally extending toward and terminating short of bottom plate 1. Slot 4 is shaped similar to slot 5 but for an extension forming a slit 7 which extends angularly to slot 25 4 and rim 2 into the curved depression 8 and/or further into said plate surface 1. The aforesaid slots have not necessarily to be arranged in opposed relation, as shown. Where the rim 21 joins the bottom plate 1, there is disposed the aforesaid curved depression 8 which is preshaped to the radius of the hollow annular rim 22 of the finished tag. One of the sections of the rim may be made of lesser height than the opposite section so as to securely and fixedly grip and hold 30 one end 9' of tie means, such as cord 9, when the latter is arranged as shown in Fig. 3. As shown in Fig. 6, the manufactured seal tag has its rim sections 2' and 3' curled over to form hollow, closed channel means to accommodate therein 35 looped string, wire, cord or other suitable tie means 9.

As shown in Fig. 2, cord 9 terminates in free legs or ends 10—10 which project from within rim section 2' therewithout. In another embodiment shown in Fig. 3, one cord end 9' is tightly and permanently gripped by and within the interior of rim section 3', whereas the other cord end 10' projects beyond slot 4 and engages frictionally with the interior of rim section 2' with 45 a force smaller than the tensile strength of said cord.

Rim 22 may be curled either inwardly or outwardly over the cord. It is important that the thickness of the cord or similar tie means is in proper relation to the space within the annular

rim or channel means so as to allow cord 9 to be slidably pulled therethrough in the direction of arrow 11 when the seal tag is being applied to an article 12 or 13 (Figs. 2 and 5). If the loop of the cord 9 of the tag is made sufficiently large, such loop can first be slipped over an article, such as for instance, a turkey wing 13, and then reduced in size to such extent that the tag cannot any more be removed. The tag can also be passed through its own loop as seen in Fig. 2, when the tag is to be secured to an elongated member 12. Legs 10 of tag 20 have sub-loop diameter becomes smaller than the diameter 10 subsequently to be pulled to the extent that the of the tag, whereby the latter will substantially abut against member 12 (in a manner similar to the showing of Fig. 5) in finally applied position of the tag. After the loop and position of the tag have thus been adjusted, the legs 10 will be wedged into slit 7, locked therein and the projecting parts of legs 10 cut off to prevent any tampering with such seal tag.

The preference of one tag over the other as illustrated in Figs. 2 and 3, depends primarily on the specific case of application.

Thus, if the loop can be slipped over an article, it will be desirable to divide the cord as shown in Fig. 3 so that only one end or leg slidably passes through section 2' of the rim, whereas the other leg end is firmly gripped and secured 30 by the curled section 3'.

The selection of the shape of the tag, whether it be round, square, oval or triangular is a matter of taste and should be determined mainly to fit the design or inscription to be printed (not shown) on the face of the tag. However, a shape where the cord is embedded in the curved rim is preferred, as it provides a better grip and lends itself better to produce a tamper-proof seal or tag.

To attach the tag according to this invention, the loop of the tie means may be slipped over a reduced portion of turkey wings 13 or hitched to 12, as shown in Fig. 2, then the ends 10 are pulled tight in the direction of arrow 11 until the loop is adjusted and tight around the article. In order to lock the cord in this position, the ends 10 are pulled in the direction of arrow 14 to wedge or lock them in slot extension 7. The protruding ends 10 are then cut off with any sharp instrument by the operator, so that, if the tag is subsequently pulled off by force, it would be impossible to attach this tag again. Since the edges of slit 7 may be made sharp and rough due to the drawing operation in the manufacture of the cup, the use of a suitable cord will permit the severance of the ends when the same are pulled in the direction of arrow 14 within the slit forming the slot extension 7. Thus, slot extension 7 may not only be considered as a locking wedge, but may also include a cutting edge or severing means for cord 9.

It is well understood that if the term "cord" is used herein, such term is intended to include any of the possible tie means which may be suitable for the purpose mentioned hereinbefore.

It will be easily visualized that the extension 7 of slot 4 may be provided directly in the flat blank when slots 4 and 5 are punched into bottom plate 1; however, it is also possible to cut such slot extension or similar locking or wedging means in the cup-shaped, half-finished seal 20, as illustrated in Fig. 1. The position of such locking means may be independent of the slot arrangement 4-5.

Although slot extension 7 is shown in wedge-shaped configuration, it is quite obvious that other suitable shapes are contemplated in accordance with this invention, whereby various thicknesses of tie means may be accommodated in the cup to finally form the seal tag.

It now becomes apparent from the above disclosure that there has been provided in accordance with this invention a tag comprising a bottom plate, a rim extending from said bottom plate and provided with slots cut across said rim, a wedge-shaped slot extension extending through said rim, said rim being curled and providing annular channel means having respective openings at said slots, and tie means positioned in said channel means, said tie means including a loop projecting beyond one of said slots and at least one leg projecting beyond another slot, whereby upon pulling of said projecting leg the extent of said loop of said tie means may be changed, said one leg being insertable in said slot extension for securement therein.

Having thus described the invention, what is claimed as new and desired to be secured by Letters Patent, is:

1. A tag comprising a bottom plate, a rim extending from said bottom plate and provided with slots cut across said rim, one slot having a wedge-shaped slot extension extending in said rim toward said bottom plate, said rim being curled and providing closed annular channel means having respective openings at said slots, and tie means located and slidably under friction in said channel means, said tie means including a loop projecting beyond one of said slots and at least one free end portion projecting beyond another slot, whereby upon manipulation of said projecting end portion the extent of said loop of said tie means may be changed, said one end portion being insertable in said slot extension for securement therein.

2. A seal tag comprising hollow channel means extending along the circumference of said tag, said channel means being provided with two spaced-apart slots whereby division of said channel means is achieved at the location of said slots, a tie member adapted to frictionally and slidably engage said channel means and extending from one of said slots through said channel means to the other of said slots to thereby form a loop at the latter slot, said tie member having at least one end projecting out of said one slot, and a slotted extension forming a prolongation of said one slot and directed angularly thereto, said slotted extension being shaped to wedgingly engage said one end of said tie member for securing the latter against removal from said channel means.

3. A seal tag according to claim 2, whereby said slotted extension further includes a sharp edge for severing said projecting end from the remainder of said tie member.

4. A seal tag comprising a hollow rim provided with a pair of slots, a tie member extending within at least a portion of said rim and frictionally and slidably engaged by the latter, said tie member having free ends normally emerging from said rim through one of said slots and extending therebeyond, a loop portion forming part 70 of said tie member and emerging from the other of said slots, and an oblique slit communicating with and forming an extension of said one slot at which the free ends of said tie member emerge, said free ends being adapted to be grasped for 75 regulating the extent of said loop portion, said

slit being shaped to wedgingly receive the free ends of said tie member upon regulation of the extent of said loop portion.

5. A seal tag comprising a hollow rim provided with a pair of slots, a tie member extending within at least a portion of said rim and frictionally and slidably engaged by the latter, said tie member having free ends normally emerging from said rim through one of said slots and extending therebeyond, a loop portion forming part of said tie member and emerging from the other of said slots, and an oblique slot cut across said rim and forming an extension of said one slot at which the free ends of said tie member emerge, said free ends being adapted to be grasped for regulating the extent of said loop portion, said slit forming a severing means for said tie member.

6. A seal tag having a hollow rim, a pair of slots in said rim, a looped cord having ends entering one of said slots and through said rim 20 and extending through the other of said slots therewithout, said cord being adapted to be

pulled under friction through said rim to tighten the loop of said cord around an article, and a slit positioned at the other slot and communicating with said rim where said ends emerge from said rim and shaped to secure said cord against movement within said rim.

7. A seal tag according to claim 6, including means at the end of said slit and adapted to sever the ends of said cord after said tag is attached to said article and said loop is tightened.
